UNITED STATES PATENT OFFICE.

HARRY SPURRIER, OF WICHITA, KANSAS.

DUPLICATING DEVICE.

Application filed March 17, 1926. Serial No. 95,434.

The object of this invention is to provide a hand duplicating device by means of which a large number of copies may be made from a wax stencil, without the necessity 5 of employing more or less expensive apparatus, or apparatus which is not readily portable.

A further object is to provide a device of the type indicated, which shall include 10 a block mounting a handle and a plurality of ink fountains adapted to feed ink thru a pad to which the ink is evenly distributed, and which is properly protected, the ink flowing thence to the stencil, in sufficient 15 quantity to provide an impression of the required clearness, without interfering with the quick drying of the printed sheets.

A further object is to provide particular 20 means for mounting the detachable elements of the device.

With the foregoing and other objects in view, the invention consists in the novel construction and arrangement of elements described, illustrated and claimed, it being 25 understood that modifications may be made within the scope of the claims, without departing from the spirit of the invention.

In the drawings forming part of this application,

30 Figure 1 shows the device in side elevation, with the ink feeding means in dotted lines.

Figure 2 is a perspective view, showing 35 one end portion of the block, and showing especially the relative position of the two ink fountains, and the spring held bar at one end of the block.

The device herein described is capable of 40 producing between one thousand and fifteen hundred copies, and if sufficient care is taken of the wax stencil a larger number may be printed.

The block 10 has secured to the upper surface thereof a handle 11, and the lower 45 surface of the block is curved, and provides an even printing surface of rocker form, from which results similar to those obtained from a cylinder machine, may be realized. Two ink receptacles or fountains 12 are provided, and these receptacles are each closed 50 by a cap such as 13, the ink being distributed thru channels or bores such as 14, which may be positioned about as shown with reference to the lower surface of the block, on

each side thereof, that is, on each side of 55 the central longitudinal axis.

The lower surface is covered by two layers of felt designated 15, and below the latter is a layer of pure linen designated 16, in order that no particles of felt may pass to 60 the openings thru the stencil to be mounted below the layer of linen. The ends of the felt layers, and the linen layer, drawn tightly before being fastened, are secured under 65 metallic bars or strips, designated 18 and 19, these strips being secured by screws 19'.

The wax stencil 20 carries a strip of cardboard on one end thereof, for reinforcing purposes, the stencil and strip being apertured, and the apertured portions being designed to pass over screws 21 which have their heads projecting from the right hand end of the block 10. It will be observed that the block at this end is provided with a 70 cutaway portion affording a straight shoulder at 22, and the opposite end is also cut away providing a transverse groove as shown at 23. Within this groove 23, I mount a rod or bar 24, having a rubber cover 25, the ends of the bar being adapted for connection with coiled springs such as 26, secured at 27. The bar or roller thus provided and including the elements 24 and 25, is adapted to resiliently engage the end of 75 the wax stencil 20, at this end of the block, the stencil extending into the grooved portion 23, and being there engaged by the roller just referred to.

Having thus described the invention, what 80 is claimed is:

1. In a device of the class described, a block having cutaway portions beneath the ends thereof, and extending transversely of the block, providing shoulders, fibrous sheets connected with the block beneath the shoulders, a stencil below the fibrous sheets and having one end detachably connected with the block above the shouldered portion, the other end of the stencil entering the cutaway portion adjacent to the other shoulder, a transverse element engaging this end of the stencil, and movable outwardly from the end of the block, and tension springs, expandable independently and longitudinally for holding the transverse element and stencil in position by engagement with opposite ends, and permitting independent movement 100 of the ends of the transverse element.

2. In a device of the class described, an element having a lower curved surface and openings therethrough, a handle connected with this element, one outer end of said element being grooved transversely, a fibrous inking sheet extending over the curved surface, means for detachably connecting a stencil with the other end of said curved

element, a roller cooperating with the transverse groove and longitudinally expansible 10 springs independently engaging opposite ends of the roller for resiliently retaining the roller and holding the adjacent end of the stencil in the groove.

In testimony whereof I affix my signature.
HARRY SPURRIER.
